UNITED STATES PATENT OFFICE.

FRANK H. FREDETTE, OF NEWARK, NEW JERSEY.

BASEBALL GAME.

Application filed November 6, 1924. Serial No. 748,124.

To all whom it may concern:

Be it known that I, FRANK H. FREDETTE, a citizen of the United States, residing in the city of Newark, county of Essex, and 5 State of New Jersey, have invented a new and useful Improvement in Baseball Games, of which the following is a specification.

My invention relates to an improved baseball game or toy wherein an imitation of 10 a baseball field is provided which simulates as closely as practicable, a baseball field. It also contemplates the use of pivoted and shiftable manikins representing the players on the field, each player being so formed as 15 to be able to catch and retain a ball of suitable size which may be driven around the field; and also means whereby the ball may be supported upon the arms of the manikin player and by a slight flip of the body of 20 the manikin is caused to be thrown about the baseball field as from the pitcher to the catcher or from one player to another.

A pivoted bat is mounted in close proximity to the home plate and is operated by 25 one person while the ball is manipulated by his opponent through the means of the manikin player. In the accompanying drawing forming a part of this specification,

Fig. 1 represents a plan view of the improved baseball game showing the edges as 30 extended in the plane of the game board.

Fig. 2 illustrates a front elevation of one 35 of the manikin players in blank form before bending the arms and supporting base.

Fig. 3 illustrates a side elevation of the 40 side showing the position of the ball if caught beneath the arms of the manikin player and also dotted lines showing the ball in position to be thrown by the manikin player.

Fig. 4 illustrates the manikin with arms and supporting base properly bent, and pivoted to the "field."

Fig. 5 represents a fractional side elevation 45 of a manikin player representing the catcher. This manikin is designed to be shifted from a point at the rear to a point immediately at the right of the home base and in front of the batter's stand.

Fig. 6 is a plan elevation of the pivoted bat.

Fig. 7 is a side view of the bat, and its support.

Similar reference numerals refer to like 50 parts throughout the specification and drawing.

The game consists of a shallow straw board box 1 of suitable size having the interior bottom laid out in the form and also the pitcher's stand 3 near the center of the field. The manikin players 4 are distributed about the field in substantially the same manner as base ball players in the regular game. Marks 5 representing the coaches' boxes are also shown near the 1st and 3rd 60 bases. A series of index circles 6 with index pointers pivotally mounted thereon are shown outside of the diamond and arranged from a point adjacent to the 3rd base to the vicinity of the catcher's station. 65

These index circles are marked to indicate the "home team" the "visitors", the "innings", "strikes and outs" and "men on bases". The out field fences 7, 8, in addition to the usual spaces for advertising matter are also marked to indicate the value of the various hits when the ball is driven within the spaces indicated; for example: when the ball is driven outside of the foul 70 line, it is indicated on the fence by the word "Foul". A ball striking the fence at "9" is considered a three-base hit. Next, near the station of the center fielder is a space marked "Single" indicating a one-base hit. 75

In the corner diagonally opposite the catcher's station is a space marked "Home run" followed by marks indicating a two base hit, a single, and a foul.

The manikins representing the players 80 are stamped out in the blank of sheet metal as indicated at 10 in Fig. 2, and are painted or colored in simulation of the regular players as indicated. The supporting base for supporting the manikins in an upright position is formed by an extension 11 85 on the feet as shown in Fig. 2, which extension is bent backwardly as shown in Fig. 3 and riveted to the bottom of the box by a tubular rivet 12, through the washer 13 in such a manner that the player can be 90 swung around to face different directions in the field.

The arms 14 of the manikins are bent forwardly and slightly upwardly inclined as 95 indicated in Fig. 3. The ball 15 used in the game is a small rubber ball of suitable size to be caught and frictionally held when rolled beneath the arms of the manikin as indicated in Fig. 3. The ball may also rest upon the arms of the manikin as indicated 100 in dotted lines in Fig. 3 and when the head of the manikin is drawn back as shown in 110

dotted lines and allowed to spring forward, the ball will be projected away from the manikin with considerable speed force. Adjacent the home plate 16 is located a low standard 17, the base 18 of which is firmly riveted to the bottom of the box. Upon the upper end of the standard is pivoted a bat 19 having a long striking part and a handle part, it being so arranged that the handle may be grasped in the fingers and given a quick and sudden spin.

Inasmuch as the catcher is required to guard the home plate from base runners, the manikin 20 representing the catcher, while in all respects the same in form and shape as the other players, is not pivoted to the bottom of the box. Two separate keepers 21, 22 of arcuate form as shown are respectively secured, one at the rear of the home plate, and the other at the front of the batter's station. In ordinary play the catcher is placed with its foot extension 11 beneath the keeper 21 to receive pitched balls. However, when the ball is in the field, the catcher may be shifted to the keeper 22 to receive the ball from any fielder and thereby cut off what would be a "run" or score.

In playing the game one person represents the ins and the other the outs. The person representing the "ins" will manipulate the bat while the person representing the "outs" will have charge of the ball 15. The ball is first placed upon the arms of the manikin representing the pitcher and the body of the manikin drawn rearwardly and then released driving the ball toward the catcher's station. The other person endeavors to strike the ball by whirling the bat. Should the ball be missed completely, the play becomes a strike. Should the bat strike the ball and drive it into the field and it is caught by one of the outfielders, this play being called "out on a fly." Should it be caught by one of the infielders and such infielder be shifted so as to throw the ball to and be caught by the 1st baseman, the play is considered as "out on first" and so on through the whole category of plays. If, however, the ball should escape the hands of both an infielder and outfielder and strike the out field fence within any of the marked spaces, the batter is credited with a hit of the value as indicated upon the space. The regular baseball rules, so far as they can be made to apply, are used in playing the game which becomes a game of science with the element of chance largely removed therefrom.

Changes in minor details of construction are contemplated and are intended to be covered by the accompanying claims.

I claim:—

1. In a baseball game, the combination of a board having a marginal barrier thereon,

a miniature baseball diamond laid out upon said board, manikin players distributed about said diamond in the usual stations occupied by such players, each player being movably secured in the station whereby said player may be faced in the direction of any other player on the field, each of said players having means for catching and holding a miniature ball, and also means for flipping said ball away from said player.

2. In a baseball game, the combination of a square board having a marginal barrier, and a miniature baseball diamond laid out thereon, with manikin players distributed about said diamond in the stations usually occupied by such players, one of said players being detachably located in the catcher's station and shiftably therefrom to a station at the side of the home plate and the remainder of said players being pivotally mounted in their respective stations, whereby each player may be faced in the direction of any other player.

3. In a baseball game, the combination of a square board marked to simulate a baseball field, and having a marginal barrier surrounding the same, said barrier having marks thereon to indicate the value of certain plays upon the field, manikin players suitably distributed about said field, one of said players being shiftably located adjacent to the home plate, and each of the remaining players being pivotally mounted in their particular station on the field and capable of facing in any direction, said players having means for propelling a ball, and means on said players for receiving a ball.

4. In a baseball game, the combination of a board marked to simulate a baseball field, with a plurality of manikin players pivotally mounted upon said board, each player formed from sheet metal blanked to shape, and having a foot extension bent at right angles to the body thereof, and arms also extending from the body at a slightly upwardly inclined angle whereby said foot extension may be utilized to secure the player in its station and said inclined arms utilized to support a ball thereon or to catch and hold a ball therebeneath.

5. In a baseball game, a manikin blanked to shape from sheet metal and marked to represent a baseball player, said manikin having a foot extension bent at right angles to the body thereof to form a supporting base, and having arms bent forwardly and slightly inclined above the horizontal to form a ball supporting and a ball catching means.

6. In a baseball game, a manikin blanked from sheet metal to simulate a baseball player, said manikin having forwardly and upwardly inclined arms forming ball supporting and ball catching means, and a foot extension whereby said manikin may be either

pivots or detachably secured to a game board.

7. In a baseball game, a manikin blanked from spring sheet metal to simulate a baseball player, and having its arms forwardly bent and slightly inclined from the horizontal, means for securing the feet of the manikin to a game board, whereby when the head of said manikin is forcibly drawn back and suddenly released a ball resting upon said arms will be projected away from said manikin.

8. In a baseball game, the combination of a game board having its upper surface marked to simulate a baseball field, manikins blanked from sheet metal and marked to simulate baseball players, said manikins each having a foot extension bent at right angles thereto to form a supporting base, a

keeper located upon said board at the rear of the home plate, a second keeper located upon said board at the side of the home plate whereby the manikin representing the catcher may be shifted from one of said keepers to the other as demanded in the progress of the game, with said foot extension extended beneath the corresponding keeper, the other manikins being suitably distributed about the field and each pivotally secured in their respective stations by their foot extensions each of said manikins having its arms forwardly bent and upwardly inclined to form a support for a ball thereon and means for catching a ball therebeneath, and a metal bat pivotally mounted upon a standard adjacent to the home plate.

FRANK H. FREDETTE.
